EDGING APPARATUS

William J. Robertson, Toledo, Ohio, assignor to
 Libbey-Owens-Ford Glass Company, Toledo,
 Ohio, a corporation of Ohio

Application September 6, 1932, Serial No. 631,789

10 Claims. (Cl. 51—74)

The present invention relates to sheet glass edging apparatus and more particularly to novel means for maintaining the glass being edged in proper contact with the edging tool.

5 In the glass surfacing art, it is customary to use a continuous type of machine for the grinding and/or finishing of the edges of glass sheets. Broadly speaking, with such a machine, a plurality of sheets of glass to be edged are vertically disposed side by side in spaced relation relative to one another and passed substantially horizontally over and in contact with one or a plurality of surfacing elements whereby to first grind and then polish the lower edges of the said sheets. It 10 has heretofore been practically impossible, however, to grind glass sheets having certain contours due to the fact that the sheets, when placed upon the machine, would have a tendency to tip or tilt either forwardly or rearwardly. This is particularly true when grinding the end edge of a sheet of glass which is not disposed at right angles with respect to the side edges thereof, in which case the upper end of the sheet overbalances the lower end thereof and tends to throw 15 it out of proper contacting relation with the surfacing elements.

It is therefore an important object of this invention to provide novel and improved means for use upon edging machines of the above character 20 by means of which it is possible to maintain glass sheets of varying contours in proper operative relationship with respect to the surfacing elements.

Another important object of the invention is 25 to provide means for securing and maintaining the glass sheets in proper contacting relation with the surfacing elements, and particularly those sheets wherein the bottom edges thereof being ground are not disposed at right angles 30 with respect to the side edges, so that as a result the sheets assume an inclined or slanting position within the machine.

Other objects and advantages of the invention 35 will become more apparent during the course of the following description when taken in connection with the accompanying drawing.

In the drawing forming a part of this application and wherein like numerals are employed to designate like parts throughout the same,

40 Fig. 1 is a side elevation, partially in section, of a portion of an edging machine with which the present invention is incorporated, and

Fig. 2 is a plan view thereof.

45 Referring now to the drawing, there is disclosed an edging machine including a supporting

framework designated in its entirety by the numeral 5 and upon which is carried the horizontally arranged channel members 6 having positioned therein the supporting runways 7 longitudinally grooved as at 8. Also carried by the framework 5 are a plurality of grinding and/or polishing wheels 9, only one of which has been shown. However, each wheel is adapted to be rotated within a receptacle 10 containing a suitable abrasive material and is driven from a shaft 11 through suitable gearing (not shown). The upper portion of the surfacing wheel 9 is received within an opening between two adjacent channel members 6, and each wheel is provided with one or more grooves 12 around the periphery thereof. 15 These grooves are in substantial horizontal alignment with the grooves 8 in runways 7. The particular construction of the surfacing wheel, together with the mounting and drive therefor, have not been illustrated in detail since they constitute no part of the present invention per se. 20

Mounted above the runways 7 and to one side thereof is a horizontally disposed endless sprocket chain 13 trained at each end of its loop about a sprocket 14, the upper run or flight of the chain 25 being supported upon and sliding over a stationary supporting member 15. The upper edges of the vertical side portions of channel members 6 constitute guide rails along which are slidable the pusher devices 16. Each of these pusher devices 30 16 comprises a horizontally disposed base member 17 resting upon and being slidable along the channel members 6, said base member carrying an upstanding dog 18 engaging sprocket chain 13 so that the pusher device is driven forwardly by the 35 lower horizontal flight of the said sprocket chain. Carried by or formed integral with the base member 17 are the spaced vertical side portions 16' which carry at each end thereof a pair of superimposed pusher rollers 20 having grooves 21 with 40 which the rear vertical edges of the glass sheets 19 are adapted to fit so that the pusher device therefore serves to advance the glass sheets forwardly in the direction indicated by the arrow in 45 Fig. 1.

Mounted above the sprocket chain 13 are the longitudinally extending spaced parallel rails 22 and 23 which slidably carry the guide member 24. This guide member is substantially rectangular in plan and comprises the side members 25 and 26 50 carried by two pairs of rollers 27 and 28 respectively which are supported upon and run along the rails 22 and 23. The rollers 27 and 28 are mounted upon axles (not shown) but which extend transversely through the side members 25 55

and 26, and also carried by these axles between the said side members are a plurality of spaced fingers 29 maintained in properly spaced relation from one another and from the side members 25 and 26 by suitable spacing collars 30. In practice, the front vertical edges of the glass sheets 19 are adapted to be received within the spaces between the side members 25 and 26 and intermediate fingers 29 so as to guide the said sheets and maintain them properly spaced from one another.

Arranged opposite each surfacing wheel 9 is a vertical standard 33 provided with a vertical slot 34 in which is slidably mounted a block 35. The block 35 and associated parts are supported by a cable 36 connected at one end to the block and passing upwardly over a pulley 37 carried by standard 33. Secured to the opposite end of the cable is a counterweight 38 which serves to counterbalance the block 35 and the parts carried thereby.

Carried by the block 35 is a forwardly directed horizontal pin or trunnion 39 upon which is pivotally mounted a sleeve 40. Carried by or formed integral with this sleeve is a rod 41 upon which is slidably a weight 42 held in the desired adjusted position by a set screw 43. Also carried by or formed integral with the sleeve 40 and extending at substantially right angles with respect to the rod 41 is an arm 44 carrying at its outer end a horizontal and forwardly directed shaft 45 upon which is rotatably mounted a roller 46, preferably formed of rubber or a rubber composition material and being provided in its periphery with one or a plurality of grooves 47 disposed in vertical alignment with the grooves 12 in the respective surfacing wheel 9. During the surfacing of the lower edges of the glass sheets 19, the upper edges thereof are adapted to be received within the grooves 47 in the corresponding roller 46. The apparatus herein described may be used for edging either laminated sheets of glass or plain sheets of glass as desired.

In the operation of the machine above described, the glass sheets 19 to be treated are first mounted upon one of the runways 7 at the forward end of the machine and placed in position for movement horizontally over the surfacing wheels 9. With the particular machine herein shown, five sheets of glass 19 (Fig. 2) of similar shape and size are arranged side by side and movable as a unit or group simultaneously over the surfacing wheels. The glass sheets 19, standing on edge with their edge to be ground facing downwardly, are then moved continuously forwardly through the machine by the pusher device 16 and maintained in proper spaced relation relative to one another by the guide member 24 as described hereinabove. The glass sheets are partially supported on edge upon the grinding wheels 9 while being ground, while the runways 7 co-operate with the grinding wheels to guidingly support the sheets during grinding thereof. As the lower edges of the glass sheets engage each surfacing wheel, the upper edges of the sheets will move beneath and in engagement with the respective roller 46 which will assist in maintaining the said sheets in a vertical position and the lower edges thereof in contact with said surfacing wheel.

The glass sheets 19 are shown in Fig. 1 as being substantially rectangular and of greater height than width. It will of course be readily understood that when the lower edges of the glass sheets to be ground are disposed at substantially right

angles with respect to the vertical side edges thereof so that the sheets assume a vertical position, little difficulty will be experienced in passing the sheets through the machine and in maintaining the lower edges thereof in proper grinding contact with the surfacing wheels. However, as pointed out hereinabove, it has been heretofore practically impossible to grind glass sheets having certain contours due to the fact that the sheets, when placed upon the machine, would have a tendency to tip or tilt either forwardly or rearwardly. This is especially true when the lower edges of the glass sheets being ground are not disposed at right angles with respect to the side edges thereof, in which case the sheets assume an inclined or slanting position within the machine in such a manner that the upper ends of the said sheets tend to overbalance the lower ends and throw the sheets out of proper contacting relation with the surfacing elements. For instance, as shown in Fig. 1, the lower edge 48 of the glass sheet 19 is not disposed at right angles with respect to the side edges 49 and 50 thereof, with the result that in order to grind the lower edge 48, the sheet must be supported and maintained in an inclined or slanting position.

In accordance with the present invention, means is provided for securing glass sheets of this particular shape and also of similar shapes in proper position within the machine, and for maintaining the lower edges thereof in proper grinding engagement with the surfacing wheels 9 during the surfacing operation. That is to say, the instant invention contemplates the provision of means for securing the glass sheets in an inclined or slanting position within the machine and for maintaining them in such position during the forward travel thereof over and in contact with the surfacing wheels. The means herein provided for this purpose comprises broadly means for connecting the pusher device 16 and respective guide member 24 together so as to maintain them in a definitely fixed relation and thereby prevent any relative movement therebetween during the surfacing operation. Such means includes a tie rod 51 secured at one end to the pusher device 16 as at 52, and a second tie rod 53 secured at one end to the guide member 24 as at 54. The inner adjacent ends of the two tie rods 51 and 53 are threaded and are connected together by means of a turn-buckle 55.

In positioning the glass sheets 19 within the machine, the said sheets are first stood on edge upon one of the runways 7 at the forward end thereof and, while held in the proper inclined or slanting position with the lower edges 48 horizontally disposed, the guide member 24 and pusher device 16 are moved to engage the front and rear substantially vertical edges 49 and 50 respectively thereof. The tie rods 51 and 53 are then connected together by the turn-buckle 55 and the turn-buckle rotated to tighten the tie rods so as to secure the pusher device and guide member in engagement with the opposite side edges of the glass sheets. Inasmuch as the pusher device and guide member are connected together so that there can be no relative movement therebetween, it will be apparent that the glass sheets will be firmly secured in proper position therebetween and will be prevented from tilting or tipping forwardly or backwardly during the grinding operation. As a consequence, the lower edges 48 of the glass sheets will be maintained in proper contacting relation with the surfacing wheels during the surfacing thereof. The rollers 75

46 engaging the upper edges of the glass sheets will also assist in holding the lower edges of the sheets in contact with the surfacing wheels.

5 It is to be understood that the form of the invention herewith shown and described is to be taken as the preferred embodiment of the same, and that various changes in the shape, size and arrangement of parts may be resorted to without departing from the spirit of the invention or the 10 scope of the subjoined claims.

10 I claim:

1. In a machine for grinding an edge of a plate of glass, the combination of grinding means upon which the glass is partially supported on 15 edge while being ground, means cooperating with the grinding means for guidingly supporting said plate of glass during grinding thereof, means engaging the rear edge of the glass plate for pushing the said plate forwardly over said grinding means, means engaging said pusher means for driving the same, means engaging the forward edge of the glass plate for guiding the same during forward movement thereof, and means independent of said driving means extending 20 between and connecting the said pusher and guide means for securing the glass plate in position therebetween.

2. In a machine for grinding an edge of a plate of glass, the combination of grinding means upon which the glass is partially supported on 30 edge while being ground, means cooperating with the grinding means for guidingly supporting said plate of glass during grinding thereof, means engaging the rear edge of the glass plate for pushing the said plate forwardly over said grinding means, means engaging said pusher means for driving the same, means engaging the forward edge of the glass plate for guiding the same during forward movement thereof, means 35 independent of said driving means extending between and connecting the said pusher and guide means for securing the glass plate in position therebetween, and means engaging the upper edge of the glass plate to assist in maintaining the said plate in a vertical position and in engagement with the grinding means.

3. In a machine for grinding an edge of a plate of glass, the combination of grinding means upon which the glass is partially supported on 50 edge while being ground, means cooperating with the grinding means for guidingly supporting said plate of glass during grinding thereof, means engaging the rear edge of the glass plate adjacent the lower end thereof for pushing the said plate forwardly over said grinding means, means engaging said pusher means for driving the same, means engaging the forward edge of the glass plate intermediate its upper and lower ends for guiding the same during forward movement 55 thereof, and means independent of said driving means extending between and detachably connecting the said pusher and guide means for securing the glass plate in position therebetween.

4. In a machine for grinding an edge of a plate of glass, the combination of grinding means upon which the glass is partially supported on 60 edge while being ground, means cooperating with the grinding means for guidingly supporting said plate of glass during grinding thereof, means engaging the rear edge of the glass plate adjacent the lower end thereof for pushing the said plate forwardly over said grinding means, means engaging said pusher means for driving the same, means engaging the forward edge of the glass plate intermediate its upper and lower ends for 65

guiding the same during forward movement thereof, means independently of said driving means extending between and detachably connecting the said pusher and guide means for securing the glass plate in position therebetween, and movable means engaging the upper edge of the glass plate to assist in maintaining the said plate in a vertical position and in engagement with the grinding means.

5. In a machine for grinding an edge of a plate of glass, the combination of grinding means upon which the glass is partially supported on 10 edge while being ground, means cooperating with the grinding means for guidingly supporting said plate of glass during grinding thereof, a pusher device engaging the rear edge of the glass plate for moving the said plate forwardly over said grinding means, a guide member engaging the forward edge of the glass plate for guiding the same during forward movement thereof, tie rods 15 respectively carried by said pusher device and guide member, and means for connecting said tie rods together whereby to secure the said pusher device and guide member in fixed relation 20 relative to one another and the glass plate in 25 position therebetween.

6. In a machine for grinding an edge of a plate of glass, the combination of grinding means upon which the glass is partially supported on 30 edge while being ground, means cooperating with the grinding means for guidingly supporting said plate of glass during grinding thereof, a pusher device engaging the rear edge of the glass plate for moving the said plate forwardly over said grinding means, a guide member engaging the forward edge of the glass plate for guiding the same during forward movement thereof, tie rods 35 respectively carried by said pusher device and guide member, means for connecting said tie rods together whereby to secure the said pusher device and guide member in fixed relation 40 relative to one another and the glass plate in position therebetween, and a rotatable roller engaging the upper edge of the glass plate to assist in maintaining the same in a vertical position 45 and in engagement with the grinding means.

7. In a plate glass edging machine of the character described, the combination of grinding means upon which the glass plate is partially supported on edge while being ground, means cooperating with the grinding means for guidingly supporting said plate of glass during grinding thereof, said plate, during grinding, being inclined in the plane of its face in such manner that the end edges thereof are not perpendicular with respect to the bottom edge being ground, means engaging the rear edge of the glass plate for pushing the said plate forwardly over said grinding means, means engaging the forward edge of the glass plate and cooperating with said pusher means for maintaining the said plate in position therebetween, and means engaging the upper edge of the glass plate to assist in maintaining said plate in a vertical position and in engagement with the grinding means.

8. In a plate glass edging machine of the character described, the combination of grinding means upon which the glass plate is partially supported on edge while being ground, means cooperating with the grinding means for guidingly supporting said plate of glass during grinding thereof, said plate, during grinding, being inclined in the plane of its face in such manner that the end edges thereof are not perpendicular with respect to the bottom edge being ground, means 70

engaging the rear edge of the glass plate for pushing the said plate forwardly over said grinding means, means engaging the forward edge of the glass plate and cooperating with said pusher means for maintaining the said plate in position therebetween, means for maintaining said pusher means and last-mentioned means in fixed relation relative to one another to prevent relative movement therebetween, and means engaging the upper edge of the glass plate to assist in maintaining said plate in a vertical position and in engagement with the grinding means.

9. In a machine for grinding an edge of a plate of glass, the combination of grinding means upon which the glass is partially supported on edge while being ground, means cooperating with the grinding means for guidingly supporting said plate of glass during grinding thereof, means engaging the rear edge of the glass plate adjacent the lower end thereof for pushing the said plate forwardly over said grinding means, means engaging the forward edge of the glass plate intermediate its upper and lower ends for guiding the same during forward movement thereof, and

means extending diagonally of the glass plate between and connecting the said pusher means and guide means for maintaining the said plate in proper position.

10. In a machine for grinding an edge of a plate of glass, the combination of grinding means upon which the glass is partially supported on edge while being ground, means cooperating with the grinding means for guidingly supporting said plate of glass during grinding thereof, means engaging the rear edge of the glass plate adjacent the lower end thereof for pushing the said plate forwardly over said grinding means, means engaging the forward edge of the glass plate intermediate its upper and lower ends for guiding the same during forward movement thereof, and means extending diagonally of the glass plate between and connecting the said pusher means and guide means for maintaining the said plate in proper position, said last-mentioned means being adjustable to move the pusher means and guide means horizontally toward or away from one another.

WILLIAM J. ROBERTSON.
